UNITED STATES PATENT OFFICE.

WILHELM SCHEERER, OF TUTTLINGEN, GERMANY, ASSIGNOR TO THE ACTIEN-GESELLSCHAFT FÜR FEIN MECHANIC, VORMALS IETTER & SCHEERER, OF SAME PLACE.

SPECULUM.

SPECIFICATION forming part of Letters Patent No. 639,444, dated December 19, 1899.

Application filed January 18, 1896. Serial No. 576,017. (No model.)

To all whom it may concern:

Be it known that I, WILHELM SCHEERER, manufacturer of surgical instruments, of Tuttlingen, Würtemberg, Germany, have invented a new and useful Improvement in Speculums, of which the following is a specification.

My invention relates to an improvement in speculums.

10 The object of the present invention is to produce a speculum in which the two upper wings overlap in such a manner that upon inserting and opening the speculum both wings will spread apart to the desired distance, while 15 at the same time overlapping each other, so as to prevent penetration of the parts between the two wings.

With this object in view my invention consists in the features, details of construction, 20 and combination of parts, which will first be described in connection with the accompanying drawings and then particularly pointed out in the claims.

In the drawings, Figure 1 is a side elevation 25 of a speculum embodying my invention. Fig. 2 is a plan view, and Fig. 3 a front view, of the same.

Referring to the drawings, A is a lower wing, preferably duck-bill shaped and provided at 30 its forward end with lateral ears a, which slope upward and outward. To the said ears the two upper wings B and C are pivotally and removably attached in a well-known manner by means of their extended and bent arms b 35 and c. The adjustment of both wings B and C is effected by a set-screw D, whose disk bears against the ends of the arms b and c and which is threaded onto the screw-bolt d, secured to a central dependent ear a', formed on the lower wing A. The said upper wings B and C when closed have a downward inclination 40 toward the end 6 of the lower wing, (see Fig. 1,) and each upper wing is rounded off or turned downwardly at the outer side, so as not to present sharp edges, which might tend 45 to cut into surrounding parts on the spreading or adjustment of said wings after insertion of the speculum. Moreover, the said wings have no reduced or shank portions connecting or uniting them with the forwardly

and downwardly extending arms b c, which form the supports therefor; but they are of such width at the forward end of the speculum as when closed to completely inclose or cover the space between the side edges 55 of the lower wing A. In this way there can be no protrusion of fleshy parts between the wings B C either when the speculum is first inserted or after the wings are spread or adjusted outwardly. Moreover, still, the said 60 upper wings are practically of equal width throughout their length, excepting that as they gradually flatten to a slight extent toward the point 6 they are slightly spread, and it will be observed that the one wing B overlaps the other, C, to a gradually-increasing extent from the points marked 1 to the points marked 2, until a complete overlapping is 65 effected. In other words, the inner edges of the said wings cross each other diagonally at 70 the forward end of the speculum, and said edges are thus continued until the inner edge of each wing is substantially flush or even with the outer edge of the other. Due to this construction, combined with the specific support for the upper wings, the said wings can 75 be adjusted or spread to as full an extent as is ordinarily required in use without inward protrusion of fleshy parts, since it will be seen that on operating the adjusting device to 80 spread the wings such spread takes place to a gradually-increasing extent from the forward to the opposite end of the speculum. It will thus be seen that the upper wings are practically closed at all positions to which the 85 same may be adjusted or spread, while at the same time the length of the screw-bolt D is such that the said wings may be spread beyond the limit of practical use, and thereby slightly separated, as shown in dotted lines, 90 Fig. 2, in order that the speculum may be easily and effectually cleaned or sterilized.

Having thus fully described my invention, what I claim as new, and desire to secure by Letters Patent, is—

1. A speculum comprising a lower wing, movable upper wings of substantially equal width throughout their length mounted at one end on one end of said lower wing, and adjustable devices for spreading the upper 100

wings, said upper wings being constructed and arranged one to overlap the other to a gradually-increasing extent lengthwise, both in the opened and closed positions of the wings, substantially as described.

2. A speculum comprising a lower wing, upper wings of substantially equal width throughout their length provided with the downwardly-extending bent supporting-arms, 10 the latter having a pivotal support upon one end of the lower wing, and the adjusting bolt and disk supported by said lower wing for moving said arms to spread the upper wings, said upper wings being constructed and arranged one to overlap the other to a gradually- 15 increasing extent lengthwise, both in the

opened and closed positions of the wings, substantially as described.

3. A speculum comprising the lower wing, upper wings having a pivotal support upon 20 one end of said lower wing, and overlapping each other to a gradually-increasing extent, both when closed and when opened in use, and means for operating said upper wings, substantially as described.

In testimony whereof I have signed this specification in the presence of two subscribing witnesses.

WILHELM SCHEERER.
